UNITED STATES PATENT OFFICE

HOWARD W. PARTLOW, OF UTICA, NEW YORK

ACTUATOR FOR FIRE EXTINGUISHERS

Application filed August 21, 1928. Serial No. 303,232.

This invention relates to an automatic fire extinguisher of the type wherein containers containing "foamite" or other extinguishing medium are arranged to discharge their contents when the container is tilted or inverted mechanically. The containers of the aforesaid type are usually mounted above or near dipping-tanks, or the like, where the hazard of fire is greatest, so as to enable the apparatus to readily and quickly smother or quench incipient fires, by discharging foam or other fluid into or around the tanks.

The object of the present invention is to provide novel construction of the actuators that control the mechanism which directly supports the containers in the ready-to-operate position. The actuators may be employed singly or in multiple and may be located in different parts of the building wherever the chief fire hazards may be. The present actuator is shown as an enclosed unit, in which is disposed a gravity air compressor, comprising an upright cylinder and a piston or plunger whose free end is enlarged to increase its weight, and by which a strong blast or pulsation of air is delivered to the container-releasing mechanism by means of a conduit, the plunger being operated by gravity during the compressing strokes, and being held in its elevated or inoperative position, by a train of novel interlocking levers, said levers being tripped for enabling the heavy plunger to gravitate, by means of an extremely sensitive thermostat. A further object is to provide means for adjusting the levers, so as to quicken or retard the action of the air compressor. And a further object is to provide means for manually elevating the compressing element for automatically setting the levers, in order to sustain said element until the thermostat operates.

I attain the objects by the means set forth in the detailed description which follows, and as illustrated by the accompanying drawings, in which—

Figure 1 is a diagrammatic view, showing the gravitational container, the container releasing means, and a plurality of distant actuators. Fig. 2 is an enlarged side elevation of the releasing mechanism. Fig. 3 is a front face view of the same. Fig. 4 is an interior view of the release with the cover removed. Fig. 5 is an enlarged front elevation of the actuator mechanism, the cover being removed, showing the air compressor partially in elevation and partially in central vertical section, the weighted plunger being in its elevated position, the interlocking levers being set to uphold the weight, and the dotted lines showing the operated positions of the several parts. Fig. 6 is a vertical section taken on line 6—6 of Fig. 5. And Fig. 7 is a vertical section taken on line 7—7 of Fig. 4, showing the release mechanism that controls the tilting of the container.

In the drawings, 2 represents an open upright frame in which is pivotally mounted a well-known type of container, as 3, for fire extinguishing fluids, the pivot 2' being so located as to enable the head 3' of the container to gravitate, to discharge the contents, as shown in Fig. 1. The head 3' is fitted with a chain or other flexible part, as 3^a, by which the container may be held elevated or inoperative by a local releasing mechanism, as 4, comprising a metallic casing 4' having one open side which may be closed by a cover, as 4^b. The top portion 4^b of the casing is cylindrical, its rear inner wall being formed with a cavity 4^c, and over this cavity is disposed a diaphragm 5, which is held in place by a disc 5^a in which is formed a complementary cavity or chamber 5^b. The chamber 4^c communicates with the port 4^d, to which a nipple 6 may be attached. The chain 3^a engages a forked lever 7 carried by the release mechanism, which is rigid on the outer end of a shaft 7' that passes transversely through the casing 4' and is jour-

naled at 4° in its opposite walls. Within the casing a collar 7^a is mounted rigidly on shaft 7', the said collar being formed with a depending arm 7^b, which is movable with the lever 7. The free end of arm 7^b is arranged to overlap the short arm 8 of a bell-crank, for holding the container in the elevated position, shown by full line in Fig. 1. This bell-crank is pivotally mounted on a shaft 8' that also passes transversely through the casing, parallel to the shaft 7'. The longer arm 8^a of the bell-crank extends upwardly beneath the shaft 7', and its top end is fitted with an adjusting screw 8^b that alines axially with the diaphragm 5, the said screw being resiliently held by a spring 8^c, in contact with the exposed end of a plunger or stem 5^c, which reciprocates in an opening in the disc 5'. The opposite or inner end of the plunger is formed with a disc-like head 5^b that engages the diaphragm 5. When the diaphragm is flexed by a blast of air delivered to the chamber 4^c, the plunger 5^c rocks the bell-crank in the direction for disengaging the tooth 8 and the arm 7^b, which releases the container 3, as may be understood by consulting Figs. 1 and 7. After the operation of the container, spring 8^c rocks the bell-crank in the opposite direction and enables the tooth 8 to again hold the lever 7 in its elevated position, shown in Figs. 1, 2, 3, 4 and 7. Immediately after the container is released, a spring 7^c lifts the arm 7^b and also the lever 7 to the inoperative position, ready to support the container, after the same has been recharged or replaced. The releasing of the container, as explained, is effected by a sudden blast of air communicated to the chamber 4^c, by a pipe 9, which connects with the nipple 6. The local releasing mechanism 4 is preferably operated by one or more thermally controlled actuators, which may be located in any convenient part of the building, as shown in Fig. 1. A description of the actuator follows:

The working parts of the actuator are supported by a base 10 having its perimeter formed with a narrow flange 10', which receives the open side of a cup-shaped casing 10^a, for completely housing of all the parts, except the thermostat 12, which is supported by a lug 10^c that is integral with the base. 13 represents generally the air compressor comprising an upright cylinder 13', which parallels the base and is provided with feet 13^a which are secured to the base by screws 13^b. The bore 13^c of the cylinder extends to a point near its bottom and is tapped by a tubular arm 13^d that extends horizontally through the closed end of the casing, to which a nut 13^e is applied for holding the casing in place. A nipple 13^f screws into the arm 13^d to which the pipe 9 connects. The open end of cylinder 13 is fitted with a solid cylindrical plunger or piston 14 whose pro-

jecting top end is disposed in an axial bore 15' that extends part way into an enlarged cylindrical weight 15, the plunger having a reduced threaded portion 14' that screws into a corresponding opening 15^a, as shown in Fig. 5. The bore 15' is enough larger than the plunger to receive a reduced portion 13^x of the cylinder when the plunger and weight descend. By this means a more compact arrangement of the actuator mechanism may be effected. The plunger 14 is held elevated, as shown in Figs. 5 and 6, by a pin 16 which is formed with a round end 16' to facilitate the quick release of the plunger when the locking pressure against the pin is relaxed. The pin 16 is held in the locking position by a short arm 17 of a bell-crank *a* which is pivoted in a split lug 16^y of the cylinder. The weight 15 is raised by a forked member 18 which is pivoted between the base and the cover and is fitted with an external handle 18', by which the member is manipulated. This forked member is normally held in its lower position, shown in Fig. 6, by gravity, the arms 18^a of said member straddling the cylinder 13 and being disposed in the path of the weight 15. The upward swing of the lever 18', as shown in Fig. 5, raises the weight and plunger and simultaneously rocks an angular member 19 which is also pivoted to the base, in the direction for shooting the pin 16 inwardly beneath the plunger 13. To this end, the member 19 is formed with an arm 19' that overlies the weight 15 and also with a similar arm 19^a that is in constant engagement with the arm 17 of the bell-crank, which in turn engages the head of pin 16. In practice, the actuator is disposed vertically and most of its working parts operate in vertical planes, as may be understood by consulting Figs. 5 and 6. The bell-crank *a* is moved towards and is held in the full-line position of Fig. 5, by the member 19 by the elevation of plunger and weight 15. At the instant the weight 15 completes its upward stroke an upright member, a sort of floating lever, as 20, moves inwardly beneath the tip of the long arm 17' of the bell-crank *a*, by the tension of a spring 21. This tends to hold the parts in the ready-to-operate position, shown in Figs. 5 and 6. The member 20 is operated against the tension of spring 21, for tripping or releasing the bell-crank *a* to enable the weight 15 to gravitate, by the thermostat 12, which comprises an expansive tube 22 that is rigidly secured in a horizontal position beneath the casing, to the lug 10^c of the base. Within the tube 22 is loosely disposed a rod 23, one end of which extends through the lug 10^c and supports a yoke-like member 23'. The opposite end of the rod extends beyond the corresponding end of the tube 22, and is fitted with a nut 23^a which engages the tube. The turning of the nut in opposite directions 130

moves the yoke towards and away from the floating member 20 and selectively determines the swing of said member relatively to the long arm 17' of the bell-crank *a*. The heating and expanding of the tube 22, as by 5 a quick rise of temperature of from ten degrees to thirty degrees in the space of one minute (according to the adjustment of rod 23), effects the swaying of member 20, by 10 means of a pair of dogs 24-24' which are pivoted within but independently of the yoke 23' to a support 24^a (see Fig. 6). The dogs 24 are virtually bell-cranks, the short arms of which are in constant engagement with the yoke 23', while the longer arms extend 15 beyond the yoke and are positioned between and engage respectively pins 20'-20^a carried by the member 20. The pull on the rod 23, by the elongation of the tube 22, spreads the long arms of the dogs and effects the outward swing of the top end of member 20, for tripping or releasing the lever *a*, which enables the weight 15 to gravitate and compress 20 the air in cylinder 13, as described. The 25 tripping of the lever *a* towards the dotted position of Fig. 5 relieves the pressure on the pin 16, and the plunger readily forces the pin outwardly and descends without restraint. This gravitation of the plunger generates a relatively strong blast of air which 30 is transmitted by pipe 9 to the diaphragm 5 of the mechanism 4, for releasing the tank 3, as explained.

My invention is extremely simple, being 35 composed of but few parts which act positively and reliably, and are not liable to get out of order. The primary actuating means comprising the thermostat 12 and related parts, are so sensitive that they operate to 40 release the containers, in from five to ten seconds time, reckoned from the flashing of the contents of a dipping-tank, and it is more or less common experience to find a fire smothered or quenched after a lapse of from 45 thirty to forty seconds following the releasing of the containers. After each operation of the actuators, all that is required of the operator to re-set the working parts is, to swing the hand-lever 18', as from the full 50 line to the dotted line position, shown in Fig. 1, or the dotted position of Fig. 5. In respect to the releasing mechanism 4, owing to the resistance offered by the cover 4 to the tension of springs 7^a and 8^a, the latter automatically 55 re-set the rocking parts 7, 7^b and 8 which cooperate to support the container in the elevated position ready for a subsequent operation.

Having thus described my invention, what 60 I claim, is—

1. In an actuator for fire extinguishers, an air compressor including a hollow upright cylinder and a weighted piston movable therein, means to manually elevate the piston, a bolt movable through an opening in the

wall of the cylinder to hold the piston elevated, a rockable member to slide and hold the bolt engaged with the piston, a member operable by the upward movement of the piston to cause the rockable member to thrust 70 the bolt beneath the piston at the end of its upward stroke, said bolt having an end formed for camming engagement with the piston, whereby upon release of the bolt by the rockable member the weight of the piston will move the bolt out of engagement therewith, a thermostat, and means actuated by the thermostat adapted to trip said rockable means for enabling the piston to gravitate for compressing the air in the cylinder. 80

2. In an actuator for controlling the release mechanism of fire extinguishers, a base, a hollow cylinder mounted on the base, a weighted plunger reciprocable in said cylinder, means to elevate the plunger, a pin 85 movable across the path of the plunger, a bell-crank to thrust and hold the pin beneath the plunger, said pin having a part formed for camming engagement with the piston, whereby upon release of the pin by the bell-crank, the weight of the piston will move the pin out of engagement therewith, a floating member to engage and prevent the accidental rocking of the bell-crank and the 90 gravitation of the plunger, a thermostat operatively connected with said member adapted when elongated by a quick rise of temperature to disconnect the floating lever and bell-crank to enable the gravitational force of the plunger to generate a strong blast of air 95 to actuate the release mechanism.

3. In an actuator for automatic fire extinguishers, a base, an air compressor comprising a hollow upright cylinder and a weighted plunger movable by gravity there- 100 in during its compression stroke, means to elevate the plunger, means adapted to be projected into the bore of the cylinder to prevent accidental gravitation of the plunger, a bell-crank to control said preventive means, 105 said preventive means being formed for camming engagement with the piston whereby upon release of the preventive means by the bell-crank the weight of the piston will move the preventive means out of engagement 110 therewith, means controlled by the upward movement of the plunger to cause the bell-crank to project said preventive means beneath the plunger, a thermostat supported by the base, and means controlled by the 115 thermostat to trip said bell-crank to enable the plunger to gravitate and compress the air in said cylinder. 120

4. An actuator for operating the release mechanism of a fire extinguisher from a distance comprising a cylinder and a plunger movable by gravity therein to generate a strong blast of air to actuate the release mechanism, means engaging the plunger to prevent accidental gravitation thereof and 125 130

having camming engagement therewith whereby gravitation of the plunger causes said plunger engaging means to be moved out of engagement with the plunger, means to elevate the plunger, means actuated by the upward movement of the plunger to operate said engaging means at the end of said movement, a floating lever to control the releasing of said engaging means, and a thermostat adapted when expanded by a quick rise of temperature to sway said floating lever for enabling the plunger to gravitate and compress the air in said cylinder.

5. In an actuator for controlling the releasable mechanism of fire extinguishers, a base, a hollow cylinder mounted on the base, a weighted plunger reciprocatable in said cylinder, a bolt movable across the path of the plunger, said bolt having camming engagement with the plunger whereby upon release of the bolt the weight of the plunger will move the bolt out of engagement therewith, a bell-crank operable by the elevation of the plunger to thrust and hold the bolt 10 beneath the plunger at the end of its upward stroke, a floating member to support the bell-crank in the holding position to prevent accidental gravitation of the plunger, a thermostat supported by the base operatively connected with said member adapted when elongated by quick rise of temperature in the vicinity of the actuator to break the connection of the floating member with the bell-crank to enable the plunger to eject the bolt 15 and gravitate for generating a strong blast of air to operate the release mechanism.

6. Means to actuate the releasing mechanism of a fire extinguisher comprising an air pump including a hollow upright cylinder and a gravitational plunger reciprocatable therein, means to manually elevate the plunger in readiness to effect the compression strokes, a stop to control the gravitation of the plunger having camming engagement 20 with the plunger whereby upon release of the stop gravitation of the plunger will move the stop out of engagement therewith, a bell-crank to move the stop beneath the plunger, a rockable member actuated by the upward movement of the plunger for effecting the engagement of the bell-crank with said stop, a floating lever cooperating with the bell-crank to hold said stop beneath the plunger, and a thermostat adapted when expanded by 25 a quick rise of temperature to sway said lever for relieving the pressure of the bell-crank against said stop to enable the plunger to gravitate and generate a sudden blast of air to operate said releasing mechanism.

60 7. An actuator for the release mechanism of fire extinguishers, including a cylinder having a gravity responsive piston therein, latching means to prevent the piston from gravitating, movable means to hold said latching means against movement, and tem-

perature controlled means to release said holding means said latching means being formed for camming engagement with the piston whereby the latching means upon release of the holding means is automatically moved by the weight of the piston out of engagement with the latter to enable the piston to descend and create a blast of air to actuate the release mechanism.

75 8. An actuator for the release mechanism of fire extinguishers, including a cylinder having a gravity responsive piston therein, latching means to prevent the piston from gravitating, movable means to hold said latching means against movement, temperature controlled means to release said holding means said latching means being formed for camming engagement with the piston whereby the latching means upon release of the holding means is automatically moved by the weight of the piston out of engagement with the latter to enable the piston to descend and create a blast of air to actuate the release mechanism, means to elevate the piston, and means operable by the elevating movement of the piston to restore said holding means and thereby the latching means to normal position.

80 9. An actuator for the release mechanism of fire extinguishers including a cylinder and a gravity responsive piston therein, means to hold the piston elevated, rocking means to move said holding means into and to retain same in operative position, means to elevate the piston, temperature controlled means to release said rocking means, said holding means being formed for camming engagement with the piston whereby the holding means upon release of the rocking means is moved by the weight of the piston out of holding engagement with the latter to permit the piston to descend and compress the air in the cylinder thereby to operate the release mechanism, and means operable by the elevating of the piston to restore said rocking means and thereby the piston holding means to normal position.

85 10. An actuator for the release mechanism of fire extinguishers including a cylinder and a gravity responsive piston therein, means to hold the piston elevated having camming engagement therewith, whereby gravitation of the piston causes the latter to move the holding means out of engagement with the piston, and temperature controlled means for normally retaining the holding means engaged with the piston and upon rise in temperature releasing the holding means for movement, thereby to release the piston for gravitation and to compress the air in the cylinder.

90 11. An actuator for the release mechanism of fire extinguishers including a cylinder and a gravity responsive piston therein, means to hold the piston elevated having camming
